(57) **CLAIM**

The ornamental design for a charging dock for an electric toothbrush, as shown and described.

DESCRIPTION

FIG. 1 is front perspective view of a charging dock;
FIG. 2 is rear perspective view of the charging dock;
FIG. 3 is a front elevational view of the charging dock;
FIG. 4 is a rear elevational view of the charging dock;
FIG. 5 is a left side elevational view of the charging dock;
FIG. 6 is a right side elevational view of the charging dock;
FIG. 7 is a top plan view of the charging dock; and,
FIG. 8 is a bottom plan view of the charging dock.

The broken lines shown in the drawings represent portions of the charging dock that form no part of the claimed design.

1 Claim, 5 Drawing Sheets
